UNITED STATES PATENT OFFICE

WILLIAM DUBILIER, OF NEW ROCHELLE, NEW YORK, ASSIGNOR TO DUBILIER CONDENSER CORPORATION, OF NEW YORK, N. Y., A CORPORATION OF DELAWARE

ELECTRICAL CONDENSER

Application filed August 4, 1926. Serial No. 127,156.

My invention relates to improvements in electrical condensers; especially condensers of a desired capacity which can be obtained with a high degree of accuracy.

5 An object of my invention is to provide a condenser so made that the capacity thereof can be adjusted to practically the exact point required and so designed that it will retain the capacity given to it as long as it is kept 10 in service.

The nature and scope of the invention are set forth in the following description taken with the drawings which show how my invention is employed in practice; and I of 15 course reserve the right to make changes as to shape, size and arrangement of the parts without abandoning the principle of the invention, or exceeding the scope of the appended claims.

20 On the drawings:

Figure 1 is a view in section of one part of my condenser;

Figure 2 is a longitudinal section of the condenser when the parts are assembled;

25 Figure 3 is a side view of what is shown in Figure 2, indicating how the condenser can be worked to give the capacity desired;

Figure 4 is a section on the line 4-4 of Figure 2;

30 Figure 5 is a longitudinal section of a complete condenser according to my invention;

Figure 6 is the top plan thereof; and

Figure 7 is a rear view thereof, enlarged.

The same numerals identify the same parts 35 throughout.

In making the condenser according to my invention, I may take a section of metal tubing indicated at 1, and inside of this section of tubing I insert a plate or sheet of 40 metal such as metal foil 2 both faces of which are covered by insulation, such as sheets of mica 3 to prevent contact being made between the metal foil 2 and the metal tubing 1. At one end the tubing is then

45 squeezed together as indicated at 4 to grip the mica sheets 3 with the mica foil between them, and the squeezed or flattened section 4 may be perforated as indicated at 5.

When the condenser is connected in circuit as by joining one terminal of the circuit 50

to the tubing 1 and the other to foil 2, the tube 1 and the sheet of foil 2 will be of opposite polarity. By inserting the flattened end 4 of the condenser between two rollers 6, I can squeeze the tube 1 into engagement 55 with the sheets of mica 3 with the metal foil between them to a greater or less extent and thus regulate the capacity. For example, as the condenser is placed between the squeezing rolls 6, the greater the portion of the 60 tube which is compressed and brought closer to the foil 2 between the mica sheets 3, the more will be the capacity given to the condenser. When the condenser is made, a piece of tubing and a sheet of foil 2 of the 65 required size are selected and then the tube is squeezed between the rollers as much as is required to impart to the condenser the capacity which is needed. The capacity of the condenser is thus set and does not afterwards vary, and at the same time the desired capacity can be obtained to a very high degree of exactness. 70

For practical use, the condenser is preferably made as shown in Figures 5, 6 and 7, 75 wherein the tube 1 is flattened to some extent throughout its length and compressed at the end 4 against the sheets of mica 3 with the sheet of foil 2 between them to a greater or less extent. Except for the portion 4 80 where the tube is squeezed against the mica sheets 3, there will be a small space between the mica sheets 3 and the inside surfaces of the tube 1, as indicated in Figures 5 and 7, and the greater the portion 4 compressed 85 against the mica sheets 3, the greater will be the capacity of the condenser. The end of the sheet of foil 2 projects beyond the mica sheets 3 and these sheets of mica may terminate within the end of the tube opposite 90 to the compressed end. To strengthen the mechanical construction of the condenser, I may utilize a pair of plates or pieces of insulation such as a phenolic condensation product 7, placing these plates so that the 95 projecting end of the sheet of foil 2 is between them, and arranging these plates 7 so that they project into the end of the tube 1 which must be compressed into engagement therewith. For example, the end of 100

the tube may be punched to provide projections 8 which enter recesses in the two pieces of insulation 7. The end of the tube thus 5 grips the insulation 7 so that this insulation cannot be withdrawn or displaced, and I can perforate the two pieces of insulation 7 and the portion of sheet of foil 2 between them and pass through this perforation an eyelet rivet 9, and secure this eyelet rivet in place 10 by expanding its ends. Then by passing a conductor through the eyelet rivet 9 which is in contact with the sheet of foil 2, the sheet of foil can be connected to one terminal of an electrical circuit, and the other terminal 15 of the circuit can be connected to the condenser, as by soldering it to the tube 1 or passing a conductor through the opening 5 of the crushed end 4. Of course, the opening through the sheet of foil 2, adjacent the 20 opening 5 should be larger than this opening, so that a conductor passing through the conductor 6 will not make contact with the foil, and the sheet of foil 2 should not be flush with the end of the squeezed portion 25 4 but should be terminated well within this end.

This type of condenser is very easy to make and it gives the capacity desired within very close limits, especially in small condensers where a low capacity is needed. The end of the tube which receives the insulation 7 can be compressed to fit around these pieces very firmly.

Having described my invention, what I 35 believe to be new and desire to secure and protect by Letters Patent of the United States is:—

1. An electrical condenser comprising a tubular casing of conductive material forming one electrode, and a sheet of conductive material forming another electrode in said casing and insulated therefrom, the casing being compressed at one end into proximity to the sheet to the required extent and having other portions spaced therefrom.

2. An electrical condenser comprising an electrode formed of a metal casing, a sheet of conductive material therein, insulating material separating said casing and conductive sheet and comprising the dielectric element of the condenser, said insulation lying within the casing and said sheet projecting therefrom, and plates of insulation on opposite sides of the projecting part of said sheet 55 and extending into the end of the casing and secured thereto, said plates and said sheet being perforated, with an eyelet rivet passing therethrough to enable connection to be made with said sheet.

3. A condenser comprising a casing of conductive material forming one armature of the condenser, a sheet of conductive material within said casing forming the other armature of the condenser, dielectric material separating said casing and conductive

sheet, a portion only of the active area of said casing being squeezed into proximity to the said conductive sheet to an extent necessary to give a proper capacity value to the condenser.

In testimony whereof I affix my signature. 70
WILLIAM DUBILIER.
